BAG CLOSURE

Meyer Korn, Brooklyn, N. Y.

Application October 17, 1955, Serial No. 540,807

10 Claims. (Cl. 229—62)

This invention relates to closure means particularly adapted for closing the open ends of containers such as bags and the like.

An object of this invention is to provide improved closure means for closing the open end of flexible walled containers such as bags or the like, the construction of the closure means being such as to allow repeated opening and closure of the container to which the same is applied.

Another object of this invention is to provide bag closure means of the character described, which is readily manipulated to effect the rapid opening or closing of a container to which the same is applied.

A further object of this invention is to provide an improved bag closure means which is adapted to tightly grip the open end portion of a bag, allowing the bag to be suspended by the closure means without slippage of the bag relative to the closure means due to the weight of the bag contents, yet allowing easy removal of the closure from the bag and repeated re-use of said closure to reclose the bag.

Still another object of this invention is to provide improved bag closure means having a structure allowing rapid application thereof to the mouth of a bag to close the same and permitting the closure to be opened by simple manipulation to gain access to the contents of the bag.

Yet a further object of this invention is to provide improved bag closure means usable with flexible walled bags of transparent or opaque material, the closure means being of a construction which aids in maintaining the shape of the bag and affords means for effectively disposing the bags on shelves or the like.

Yet another object of this invention is to provide improved, reusable bag closure means adapted to carry various indicia, markings and the like, for the purpose of clearly indicating the contents of the bag, sizes, weights and the like, as well as trademarks or other identifying insignia or markings.

Other objects of this invention will in part be obvious and in part hereinafter pointed out.

In the drawing, Fig. 1 is a plan view of the bag closure means embodying the invention, in opened up, blank form;

Fig. 2 is a perspective view of the closure means related to the container with which it is to be associated;

Fig. 3 is a perspective view of the associated closure means and container in partly folded condition;

Fig. 4 is a view similar to that of Fig. 3 showing the closure completed folded and before the locking tabs are interengaged;

Fig. 5 is a view similar to that of Fig. 4, showing the locking tabs interengaged;

Fig. 6 is a sectional view taken on the line 6—6 of Fig. 2;

Fig. 7 is a sectional view taken on the line 7—7 of Fig. 3;

2

Fig. 8 is a sectional view taken on the line 8—8 of Fig. 4;

Fig. 9 is a sectional view taken on the line 9—9 of Fig. 5;

Fig. 10 is a sectional view taken on the line 10—10 of Fig. 5;

Fig. 11 is a plan view of a modified form of the invention, in opened up blank form;

Fig. 12 is a plan view of the closure shown in Fig. 11, applied to a bag container; and

Fig. 13 is a transverse sectional view of the closure showing the anchoring of the mouth of the bag by the first fold thereof.

With the increased use of flexible walled containers, particularly bags made from cellophane, polyethylene, vinyl or epoxy resins, in both transparent and opaque forms, it is vital that the closure means used on such bags augment and enhance the utility of the bags. Thus, with a re-usable closure, the contents of the bag may be withdrawn for inspection or the like after opening such a closure; returned to the bag which is then reclosed, thereby preserving the contents from soilage or the like.

As shown in the drawings, the bag closure embodying the invention comprises a blank, indicated in Fig. 1, which may be formed of cardboard, stiffened paper, plastic sheeting, wood veneer or other materials having suitable stiffness allowing the same to retain a shape and to be scored or creased to provide panels and tabs as elements of the closure.

30 The closure comprises a rectangular panel 8 with succession of narrow folding panels 3, 2 and 1 extending from the top edge thereof; panels 3, 2 and 1 being defined by parallel crease lines *d*, *c* and *b* upon which said panels may be folded. The width of folding panel 1 is substantially equal to that of panel 2 as measured from edge *a* of panel 1 to crease line *b* and from crease line *b* to crease line *c*.

35 A pair of shallow tongues or projections 9 extend from the edge *a* of panel 1, being longitudinally spaced and having a depth measured to line *e*—*e*. On crease line *c* is formed a pair of slots 10 aligned with tongues 9 and adapted to receive the same, as later described.

40 The closure further includes elongated tabs 4, 4' extending respectively from the opposite ends of panel 8, 45 with intervening narrow fold panels 5 formed by creasing or scoring. The width of panels 5 is substantially equal to that of panel 3. The tab 4 is formed with a tongue 7 at the outer end thereof which is receivable in slot 6 formed in tab 4'.

50 The closure of the instant invention may be associated with bags of various shapes, forms and dimensions; formed from paper, cellophane, polyethylene, vinyl or other resin sheeting, fabric and the like. As shown in Figs. 2, 6, the open end of the container is disposed over 55 the inner surfaces of panels 8, 3 and 2, the panel 1 is folded downwardly on crease line *b* toward panel 2 and tongues 9 are pressed against linear portions of the container walls, displacing the same out of their plane and forcing the same through slots 10, as shown in Figs. 3 and 7. Thus, the marginal portion of the container is locked between panels 1 and 2 and securely anchored in place by tongues 9 received in slots 10.

55 The panels 1, 2 are further folded on crease line *c* towards panel 8, as shown in Figs. 4 and 8; and tabs 4, 4' are folded toward each other and interengaged through tongue 7 received in slot 6 of tab 4', thus maintaining the panels 2, 1 from unfolding. Narrow panels 3, 5 provide thickness for the closure, to allow the contents of the container to extend into close proximity to the 60 mouth thereof and to be disposed between panels 8 and folded panels 1, 2. It is understood that if the contents of the container do not extend to the lower edge of clo-

sure panel 8, then panels 3 and 5 may be omitted, and folded panels 1, 2 will lie close to panel 8 with the interlocked and positively anchored bag end secured therebetween.

It is further understood that the tongues 9 may be varied in number and longitudinal disposition, as well as longitudinal dimension, in accordance with the nature of the material from which the container is formed, to insure proper anchorage in slots 10 without tearing of the container material.

Panels 8, 2, 3 and 5 afford on their outer surfaces means for imprinting thereon indicia and markings of all kinds to show sizes, weights, source of manufacture, trademarks, ornamental matter and the like. Furthermore, the closure lends shape to the container and the contents thereof. The bag container with the closure of the instant invention lends itself to storage on shelves with the closure extending forwardly and panel 3 thereof visible to display the markings thereon.

A modified form of closure is shown in Figs. 11 and 12, wherein the slots 10 are replaced by slits 10a formed in the crease line c; short cross slits 11 being formed in panel 8 at the opposite ends of slits 10a, to provide short, bendable tabs 12 which are engageable by tongues 9 when panel 1 is folded on crease line b toward panel 2. Thus, the tabs 12 are bent outwardly by tongues 9 to become interengaged therewith, taking with the tongues linear portions of the bag material for positively anchoring the same, as previously described.

Also, end tabs 4, 4' may be replaced by wing shaped members 13, 13' foldable toward each other and toward panel 8 on crease lines 14. The members 13, 13' include tabs 15 extending laterally outward of the lower portions thereof and arm portions 16 extending laterally outward of the upper portions thereof, said portions 16 being longer than tabs 15 and extending parallel thereto. Panel 2 is formed on the central portion thereof with a pair of transverse slots 17.

As shown in Fig. 12, after the mouth portion of the bag container has been interlocked between panels 1, 2 and anchored in place by tongues 9 and interengaging tabs 12, the members 13, 13' are folded toward each other and in superposed relation, tabs 15 being inserted in slots 17, to retain folded panels 1, 2 against panel 8 and to dispose arm portions 16 in a manner to provide handle means, leaving a space 18 to receive the fingers when overlapping arm portions 16 are grasped to carry the bag container and the contents thereof.

It is understood that the closure shown in Figs. 1-4 may be similarly modified to provide handle means as shown in Figs. 11, 12. Furthermore, one of the arm portions 16 and that portion of member 13 immediately below arm portion 16 may be omitted, leaving the other arm portion 16 on member 13' to form a hook shaped member for hanging the bag container from a suitable support.

As various changes might be made in the embodiments of the invention herein shown, without departing from the spirit thereof, it is understood that all matter herein shown or described shall be deemed illustrative and not by way of limitation except as set forth in the appended claims.

Having thus disclosed my invention, I claim as new and desire to protect by Letters Patent:

1. In combination with a flexible walled container, closure means comprising a base panel, a pair of adjacent panel portions foldable over each other and extending successively from the top edge of said base panel, said adjacent panel portions being adapted to receive therebetween the open end walled portion of said container, interengageable means on said adjacent panel portions for directly engaging therebetween wall portions of said container and anchoring the same between said adjacent panel portions, said adjacent panel portions being foldable toward said base panel, and tab means extending from opposite ends of said base panel and foldable over

each other to retain the folded adjacent panel portions in overlying relation to said base panel, said tab means including interengageable connecting means.

2. In combination with a flexible walled bag, closure means comprising a panel adapted to be disposed on one side of said bag adjacent the mouth thereof, a plurality of successive, hinged panels extending from the top edge of said first mentioned panel and foldable toward each other to interlock therebetween, the mouth portion of said bag, and interengageable means on said last mentioned panels for displacing a linear portion of said bag walls out of the plane thereof and positively gripping said displaced wall portions to retain the mouth portion of said bag against slipping between said last mentioned panels.

3. The combination as in claim 2 wherein said last mentioned panels and the interlocked portion of said bag are foldable toward said first mentioned panel, and foldable tab means extending from the opposite ends of said first mentioned panel for overlying said last mentioned panels and including interengageable portions for retaining the same adjacent said first mentioned panel.

4. Bag closure means comprising a base panel, adjacent panel portions foldable over each other and extending from the top edge of said base panel, a shallow tongue projecting from an intermediate portion of the outer edge of the outermost of said panel portions, means disposed between the innermost of said panel portions and said base panel releasably engageable by said tongue for locking said panel portions together, and tabs extending laterally from said base panel at the opposite ends thereof, said tabs being foldable toward said base panel, and means for retaining said tabs in superposed relation to said base panel.

5. Closure means as in claim 4 wherein said panel portion locking means comprises a longitudinally extending slot for receiving said tongue.

6. Closure means as in claim 4 wherein said panel portion locking means comprises a displaceable tab engageable by said tongue for interlocking engagement.

7. Closure means as in claim 4 and further including an arm extending from at least one of said tabs and disposed parallel to and above said tab.

8. Closure means as in claim 4 and further including an arm extending from each of said tabs and disposed parallel and above said tabs, said arms being adapted to be superposed to form handle means for said closure.

9. Closure means as in claim 4 wherein said tab retaining means comprises transversely disposed slots formed in the innermost panel portion for receiving end portions of said tabs.

10. In combination with a flexible walled bag, a bag closure, comprising a stiff, shape retaining sheet member formed with parallel crease lines to provide a plurality of longitudinally extending hinged panels, a pair of said panels being foldable along crease lines into opposed relation to receive therebetween a marginal mouth portion of said bag, and tongue means on one of said pair of panels displaceable from the plane thereof and in contact with a wall portion of said bag for displacing the same from the plane of said bag wall, and means releasably engageable with said tongue means for releasably gripping said displaced wall portion therebetween.
